UNITED STATES PATENT OFFICE.

DEWIS LANDAU, OF SAN FRANCISCO, CALIFORNIA.

SIPHON-BOTTLE.

No. 801,831.

Specification of Letters Patent.

Patented Oct. 10, 1905.

Application filed April 28, 1905. Serial No. 257,868.

To all whom it may concern:

Be it known that I, DEWIS LANDAU, a citizen of the United States, residing at San Francisco, in the county of San Francisco and State of California, have invented certain new and useful Improvements in Siphon-Bottles; and I do hereby declare the following to be a full, clear, and exact description of the invention, such as will enable others skilled in the art to which it appertains to make and use the same.

Generally speaking, this invention is an improvement in siphon-bottles, but to be more specific it consists in devices whereby the bottle can be readily refilled through the agency of such attachments as shown in my former application, Serial No. 242,666, bearing date of January 25, 1905.

The several parts are absolutely automatic in their operation, opening the moment suitable pressure is directed from the attachment and closing the moment the pressure is removed in the act of withdrawing the bottle.

The device is adapted to be used in conjunction with any form of siphon-head, as the refilling occurs through a secondary pipe, as shown in my former applications for patents, Serial Nos. 209,766 and 220,047, and bearing dates of May 25, 1904, and August 30, 18, 1904, respectively, and not through the spout.

Other objects and advantages of the invention will appear in the following specification, and the novel features thereof will be particularly pointed out in the appended claims.

In the drawings hereunto annexed and constituting a part of this specification, Figure 1 is a side elevation and partial section of a siphon-head, showing the relative position of my invention. Fig. 2 is a section of the device positioned on the ordinary form of siphon-head. Fig. 3 is a perspective view of the spring-pressed valve employed.

I will now explain the construction of the several parts of my invention and subsequently describe the operation of the same, reference being had to the above views by letter.

The main body of the siphon-head is formed in the usual manner with the siphon-tube A, spout B, spring-pressed valve C, and metal collar D, the latter for binding the head to the neck of the bottle E. Formed integral with the siphon-head and leading to

the interior of the siphon-tube A is the secondary pipe F, which is formed with exterior threads and the interior seat f. Adapted to engage with the exterior threads on the secondary pipe F is the cap G, which is contracted in diameter to form the hollow nipple g. Within this cap G and resting against the rim of the secondary pipe F is the yielding washer H. Arranged to slide snugly within the hollow nipple g is the hollow stem i of the valve I, the rim of the enlarged head i' of which engages with the inner face of the yielding washer H. This rim of the head i' is formed with a groove from which lead the passages a to the interior of the hollow stem i. Interposed between the head i' and the seat f is the compression-spring J, which encircles a contracted flange on the head i'. This spring evidently causes a normal close seal between the rim of the head i' and the washer H.

Now from the description so far gone into it is evident that, assuming that soda or other liquid can flow from the nozzle K under suitable pressure, by forcing the stem i against the nozzle K the former will yield until the head i' leaves the washer H, when the soda is free to pass through the hollow stem i, passages a, secondary pipe F, and finally through the siphon-tube A to the interior of the bottle. By simply withdrawing the cap G from the nozzle K the spring J will immediately force the head i' against the washer H, and thereby prevent the back-flow of the soda from the bottle.

As a means for clamping the bottle to the attachment from which the soda is received I have provided the projecting flange M on the outer periphery of the cap G, thereby affording a suitable projection to engage with any suitable lever or clamp on the attachment.

From the above description it is manifest that the bottle can be readily and quickly refilled and detached from the stationary supply attachment, or in case it is desired to use the bottle as a stationary fixture it can be clamped to the attachment and supported on a neat stationary support and the soda continuously drawn and the bottle simultaneously refilled. This automatically-operated valve situated in the secondary pipe does not in the least hinder the free operation of the valve which controls the flow of the soda through the ordinary spout, and

this fact makes my present invention applicable to siphon-heads of varied and usual construction.

There are various forms which this device 5 may take on and still be within the spirit of my invention, and I therefore do not wish to confine myself to the exact construction and proportion of parts herein shown and described.

10 What I claim as my invention is—

1. In combination with a siphon tube and spout, a secondary pipe leading to said tube and through which the siphon-bottle is filled, a spring-pressed valve in said secondary pipe 15 and arranged to automatically operate to prevent the escape of the contents of the bottle substantially as set forth.

2. In combination with a siphon tube and spout, a secondary pipe leading to said tube 20 and through which the siphon-bottle is filled,

a spring-pressed valve arranged to close the passage through said pipe, a nipple on said valve, said valve being arranged to open as pressure is directed against said nipple and automatically close as said pressure is withdrawn for the purpose set forth. 25

3. In combination with a siphon tube and spout, a secondary pipe leading to said tube and through which the siphon-bottle is filled, a screw-cap engaging said pipe, and a spring-pressed valve arranged to control the flow of liquid through said pipe for the purpose set forth. 30

In testimony whereof I have hereunto signed my name to this specification in presence of two subscribing witnesses. 35

DEWIS LANDAU.
